SINGLE LOBE WASHING MACHINE PUMP

Herbert F. Prasse, Gates Mills, Ohio, assignor to Thompson Ramo Wooldridge Inc., a corporation of Ohio

Filed Sept. 10, 1957, Ser. No. 683,123

8 Claims. (Cl. 103—83)

This invention relates generally to pumps and more particularly to improvements in a single lobe-bladed impeller pump capable of pumping both gaseous and liquid fluid as may be required in use with washing machines and the like, although other uses and purposes of the invention will be apparent to one skilled in the art.

In pumps of the type disclosed herein, the porting plug is subjected to expanding action due to moisture absorption and high temperature operation of the pump. In accordance with the principles of the present invention, a porting plug is restrained from expanding excessively by providing bushings which are pressed on the outside diameter of the plug rather than into the inside diameter of the impeller, thereby restraining the plug from growing excessively.

Moreover, in pumps of the type disclosed herein utilized in an environment such as that provided by a laundry machine, foreign particles such as lint are frequently carried in the pumping medium and accumulations are likely to build up in the clearance spaces. In accordance with the principles of the present invention, the impeller is provided with water circulating means such as venting passages, thereby permitting some water to circulate in the clearance spaces between the ends of the impeller and the bearing cap and housing and preventing the build-up of lint or foreign particles in the clearance spaces.

It is an object of the present invention, therefore, to provide an improved pumping device which overcomes the deficiencies of the prior art.

Another object of the present invention is to provide a single lobe pump of the liquid ring-type wherein means are provided to prevent excessive expansion of the porting plug due to moisture absorption and high temperature operation of the pump.

Yet another object of the present invention is to provide a liquid ring-type pump having means to prevent build-up of foreign particles in the clearance spaces within the interior of the pump.

Still another object of this invention is to provide a single-lobe pump of the liquid ring type, wherein only one intake and one exhaust port is required, and wherein the feeding of fluid to the exhaust zone and outlet is greatly simplified by an improved port plug.

A further object of this invention is to provide a pump of the stated type which is characterized by ease of manufacture and facility of operation, and wherein effective means are provided for journaling the annular impeller while at the same time constraining the port plug to prevent swelling due to heating or moisture absorption.

A still further object of this invention is to provide a pump of the character described wherein the principal elements are formed of a suitable plastic such as polystyrene or the like and in which the operative elements are so arranged as substantially to reduce friction losses.

Another object of the invention is to provide a pump of the stated type particularly suitable for use in washing machines in which the ends of the annular impeller are spaced from the pump housing to reduce frictional losses and in which means are provided for introducing pressure fluid into the spaces thus formed to remove accumulations of lint.

Another object of the invention is to provide a liquid ring pump which is characterized by operation at a

2

relatively low noise level due to the elimination of the usual double lobe, double port arrangement which results in the formation of wave fronts due to impulses from two exhaust ports meeting in a single outlet pipe.

Other objects, features and advantages of the invention will be apparent from the following detailed description, taken in conjunction with the accompanying sheets of drawings, wherein like reference numerals refer to like parts, and in which:

10 On the drawings:

FIGURE 1 is an end elevational view of a pump constructed in accordance with the principles of the present invention;

15 FIGURE 2 is a cross-sectional view with parts in elevation, taken substantially along line II—II of FIGURE 1, and with certain parts omitted for the sake of clarity;

FIGURE 3 is a transverse sectional view taken substantially along line III—III of FIGURE 2;

20 FIGURE 4 is a fragmentary and broken axial sectional view taken in FIGURE 1, with some parts in elevation, and taken substantially along the lines IV—IV;

FIGURE 5 is a fragmentary end elevational view of the drive shaft end of the pump.

25 As shown on the drawings:

Referring particularly to FIGURES 2 and 4, the pump of the instant invention comprises a pump of the liquid ring type and includes generally a pump housing 10, a pump cover member 11, an impeller 12, a porting plug 13, and a drive shaft 14.

30 The pump housing, cover member, impeller and porting plug are molded or cast from a thermoplastic or thermosetting synthetic resin, such as polystyrene, resistant to water carried detergents, capable of withstanding temperatures elevated to 200° F. without distortion, and easily shaped and fabricated as pump components within the limits of operating tolerances without requiring machining.

35 The housing 10 includes a main body portion 15 of generally cylindrical shape within which is formed a pumping chamber 16 including a portion referred to herein as a single lobe displacement chamber 16a most clearly shown in FIGURE 3. The chamber 16a as illustrated, is preferably formed by positioning the impeller in an eccentric position with respect to the pumping chamber 16. This forms in effect a lobe at one side of the chamber 16. The chamber 16a is a lobe with respect to the portion of the chamber 16 occupied by the impeller 12 so that this pumping chamber may be herein referred to as a single lobe chamber.

40 At one end of the casing or housing 10, there is provided an end wall 18 terminating in a reduced tubular extension 19 provided with a bore 20. A counterbore 20d is formed between the pumping chamber 16 and the bore 20.

45 At the opposite end of the casing or housing 10, there is provided a flange 17 to which is attached the cover member 11, a plurality of suitable fasteners being indicated at 29.

50 The cover member 11 has a tubular extension 11a provided with a bore 26 and is progressively counterbored as at 25, 24 and 23, there being radially extending shoulders provided between each adjacent pair of counterbores.

55 The impeller of the present invention, as indicated generally at 12, comprises an annular row of circumferentially spaced vanes or blades 30 which are integrally joined at their opposite sides to a pair of axially spaced annular end plates 31 and 32. The vanes 30 are tapered from the outer radial edge to the inner radial edge to form 60 passageways 33 between the vanes of substantially uniform cross-sectional area.

65 The porting plug 13 of the present invention is partic-

ularly characterized by the provision of two bushings 52 and 54, respectively, which are pressed or molded on the outside diameter of the porting plug 13. The bushings 52 and 54 constitute rings or sleeves which restrain the plastic porting plug 13 from expanding excessively due to moisture absorption or high temperature operation of the pump. It will be noted that the bushings 52 and 54 are pressed on the outer diameter of the porting plug 13 rather than into the inside diameter of the impeller 12. Such arrangement accomplishes the restraint in growth desired in accordance with the principles of the present invention since the bushings 52 and 54 act as bands to restrain the porting plug 13 from growing excessively.

The bushings 52 and 54 develop an additional function in that the bushing 52 has a bearing surface 52a and the bushing 54 has a bearing surface 54a. The bearing surfaces 52a and 54a are spaced apart from one another longitudinally and provide a journal and bearing support for rotatably supporting the impeller 12 on confronting bearing surfaces 52b and 54b provided at longitudinally spaced points within a center bore 12a extending longitudinally through the interior of the impeller 12.

As shown in the drawings, the end plate 31 of the impeller 12 is spaced from the adjoining surface of the end wall 18 thereby leaving a clearance space indicated at Z. Likewise, the end plate 32 is spaced from the adjoining surface of the cover member 11 to provide a clearance space indicated at Y.

In accordance with the principles of the present invention, the end wall 31 is provided with an axially extending aperture or venting opening 31a and the end wall 32 is likewise formed with an axially extending opening or venting aperture 32d. Some of the fluid being pumped is thus permitted to circulate in the clearance spaces Y and Z between the ends of the impeller 12 and the bearing cap and housing formed by the housing 10, the end wall 18 and the cover member 11. Such circulation prevents lint or other foreign particles from building up in the clearance spaces Y and Z and considerably enhances the satisfactory operation of the pump. As will be appreciated, the pressure in the clearance spaces Y and Z will always be somewhere between the inlet and outlet pressure of the pump inasmuch as there is slight communication between the clearance spaces Y and Z and the passageways 33 between the vanes of the rotor over the outer peripheral edges of the annular end plates 31 and 32 and some of the passages are at inlet pressure and others are at outlet pressure. When the passageway 33 which is exposed to the venting openings 31a and 32d is at inlet pressure fluid flows from the clearance spaces Y and Z into said passageway 33. When the same passageway is at outlet pressure fluid flows out through the openings 31a and 32d into the annular spaces Y and Z.

The casing or housing 10 is formed with an inlet 21 and an outlet 22. To divide the fluid flow therebetween, the porting plug 13 includes an elongated plate-shaped main body 39 extending substantially diametrically across the cylindrically reduced casing section 20 and the central bore 12a of the impeller and longitudinally from the end of the casing or housing 10 to the opposite end of the impeller 12.

In operation, fluid enters the intake port 21, flows into the intake zone at one side of the porting plug 13, is drawn into the passages 33 of the vanes 30, and is impelled radially outwardly into the lobe 16a. The fluid is forced through adjacent vane passages from the lobe 16a to the outlet zone on the other side of the plug 13 and flows outwardly through the outlet 22.

To rotatably drive the impeller 12, the drive shaft 14 is rotatably journaled on bearing surfaces indicated at 35 received in the bore 26 of the tubular extension on the cover member 11. A shaft seal is provided as at 36 and a pilot portion 14a on the end of the drive shaft 14 projects into a recess formed in one end of the porting plug 13. A splined driving connection is effected

between the impeller 12 and the drive shaft 14 by cooperating external splines 34b and internal splines 34a.

Although minor modifications might be suggested it should be understood that I wish to embody all such modifications as are reasonable and proper within the scope of the patent warranted thereon.

I claim as my invention:

1. A pump including a housing having an inlet and an outlet, a drive shaft bearingly supported by said housing, an impeller in said housing drivingly connected to said shaft, said impeller being diametrically smaller than the inner housing wall and eccentrically mounted with respect to said housing, an axial bore through said impeller communicating through the periphery of the impeller with the interior of the housing and coaxial with the axis of rotation of the impeller, a porting plug fixed in said housing and extending axially into said bore made of a material subject to expansion due to moisture absorption at high temperature operation of the pump and having a portion extending across the bore dividing the impeller bore into an inlet zone and outlet zone, means connecting said zones respectively with said inlet and said outlet, and a pair of axially spaced bushings non-rotatably mounted on said porting plug made of a material of sufficient stability to prevent swelling of said porting plug and forming bearing surfaces journaling said impeller.

2. A pump including a substantially cylindrical housing having an inlet and an outlet, an annular impeller rotatably carried in said housing in eccentric relation thereto, a drive shaft connected to said impeller, an axial bore into the impeller communicating with the impeller and the periphery of said impeller and coaxial with the impeller axis, and a stationary porting plug fixed in said housing extending into the bore of said impeller and having a portion extending across the bore and coating with surrounding impeller structure to form passages communicating an arcuate portion of said impeller bore with said inlet and a diametrically opposed arcuate portion of said bore to said outlet, said porting plug being made of a material subject to expansion due to moisture absorption and high temperature operation of the pump and being provided with bushing means nonrotatably located on the plug and made of a material having sufficient stability for constraining swelling thereof and forming bearing members journaling said impeller.

3. A pump including a substantially cylindrical housing having an intake port and an outlet port, an annular impeller rotatably carried in said housing in eccentric relation to the inner housing walls, a drive shaft connected to said impeller, a bore in the impeller communicating through the periphery of the impeller with the interior of the housing and coaxial therewith, and a stationary porting plug fixed in said housing extending into said bore coating with surrounding impeller structure to form passages intercommunicating a first arcuate portion of said impeller bore and said intake port and a second arcuate portion of said impeller bore and said outlet port, said second arcuate portion being substantially diametrically opposed with respect to said first arcuate portion, said porting plug being made of a material subject to expansion due to moisture absorption and high temperature operation of the pump and provided on the outside diameter thereof with a pair of axially spaced metal bushings non-rotatably mounted on the plug constraining swelling of said porting plug due to moisture absorption or a rise in temperature and forming bearing surfaces journaling said impeller.

4. A pump including a housing having an inlet and an outlet, a pumping chamber in said housing, an annular impeller rotatably mounted in said chamber and cooperating therewith to form a single lobe, a drive shaft connected to said impeller, a bore coaxial with the impeller axis and communicating through the impeller at the periphery thereof with the pumping chamber, a porting plug fixed in said housing extending axially into the

impeller bore and having a portion extending across the bore dividing the impeller bore into an inlet zone and an outlet zone, means connecting said zones respectively to said inlet and said outlet, said porting plug being made of a material subject to expansion due to moisture absorption and high temperature operation of the pumps, means for supporting the porting plug in the housing, and a pair of axially spaced metal bushings mounted non-rotatably on the outside diameter of said plug constraining swelling of said porting plug.

5. A pump including a housing having an inlet and an outlet, a pumping chamber in said housing, an annular impeller rotatably mounted in said chamber and cooperating therewith to form a single lobe, a drive shaft connected to said impeller, said impeller having annular end plates spaced from said housing forming a pair of annular chambers, vent means in each of said end plates for circulating working fluid between the impeller and said annular chambers, a bore in said impeller communicating through the periphery of the impeller with the pumping chamber and coaxial with the axis of rotation of the impeller, means supported in the housing extending across said impeller bore dividing said bore into inlet and outlet zones in circumferentially displaced locations, and means connecting said zones respectively to the inlet and outlet of said housing.

6. A pump including a housing having an inlet and an outlet, a pumping chamber in said housing, an annular impeller rotatably mounted in said chamber and eccentrically positioned with respect to an axial center line extending through said chamber thereby forming with the walls of said chamber a single lobe pumping space, said impeller having annular end plates spaced from said housing thus forming a pair of annular chambers, venting means in said end plates forming openings for circulating working fluid between the impeller and said annular chambers, a drive shaft connected to said impeller, a bore in the impeller coaxial with the impeller axis and communicating through the periphery of the impeller with the pumping chamber, and a porting plug supported in the housing extending axially into said impeller bore and dividing the bore into an inlet zone and an outlet zone connected respectively to the inlet and the outlet of said housing.

7. A pump including a housing having an inlet and an outlet and having an annular outer wall and end walls, a pumping chamber in said housing, an annular impeller rotatably mounted in said chamber and eccentrically positioned with respect to the axial center of said chamber thereby forming with the walls of said chamber a single lobe pumping space, said impeller having end

plates in spaced relation to adjoining end walls of said housing thus forming a pair of annular chambers, a vent opening means in each of said end plates for circulating working fluid between the impeller and said annular chambers, a drive shaft connected to said impeller, a bore in the impeller coaxial with the impeller axis and communicating through the periphery of the impeller with the pumping chamber, a fixed porting plug supported in the housing extending axially into said impeller bore and dividing the bore into an inlet zone and an outlet zone, and means connecting said zones to communicate respectively with the inlet and the outlet of said housing.

8. A pump including a housing having an inlet and an outlet and having an annular outer wall and end walls, a pumping chamber in said housing, an annular impeller rotatably mounted in said chamber and eccentrically positioned with respect to an axial center extending through said chamber thereby forming with the walls of said chamber a single lobe pumping space, said impeller having annular end plates in spaced relation to adjoining end walls of said housing thus forming a pair of annular chambers, each of said end plates being provided with a vent opening means affording circulation of fluid between the impeller and said annular chambers, a bore in the impeller coaxial with the impeller axis of rotation and communicating through the periphery of the impeller with the pumping chamber, a porting plug supported in the housing extending axially into said impeller bore and dividing the bore into an inlet zone and an outlet zone, means connecting said zones to communicate respectively with the inlet and outlet of said pump, and a pair of axially spaced bushings on the outside diameter of said plug constraining swelling thereof and journaling opposite ends of said impeller.
